UNITED STATES PATENT OFFICE.

GEORGE H. DROEGE, OF NEW YORK, N. Y., ASSIGNOR TO CENTURY
MANUFACTURING COMPANY, OF NEW YORK, N. Y.

DESIGN FOR A STOVE-LEG.

SPECIFICATION forming part of Design No. 36,177, dated December 23, 1902.

Application filed November 28, 1902. Serial No. 183,143. Term of patent 3½ years.

To all whom it may concern:

Be it known that I, GEORGE H. DROEGE, a citizen of the United States, and a resident of the city of New York, borough of Brooklyn, in the county of Kings and State of New York, have invented and produced a new, original, and ornamental Design for a Stove-Leg, of which the following is a specification, reference being had to the accompanying drawing, forming a part thereof, in which is represented a face view of a stove-leg embodying the features of my design.

The design consists in a main scroll A, extending from one side of the leg to the other near the top and terminating in inward curls, a central closed scroll-panel B, resting on the main scroll A and provided with a fan-like ornamentation C, and intermediate scrolls D, having curled terminals extending in opposite directions to the curled terminals of the

main scroll, sundry openings appearing between the intermediate scrolls, and the intermediate scrolls and the main scroll, and the intermediate scrolls and the scroll-panel, together with a longitudinal box-fluting E, 25 which constitutes the decoration for the main portion of the leg below the main scroll A.

Having thus described my invention, I claim as new and desire to secure by Letters Patent—

The ornamental design for a stove-leg herein shown and described.

In testimony whereof I have signed my name to this specification in the presence of two subscribing witnesses.

GEORGE H. DROEGE.
